UNITED STATES PATENT OFFICE

170,718

COMBINATION OUTDOOR FIREPLACE AND GRILL

Edward D. Ringwall, West Haven, Conn., assignor to The Howard Company, New Haven, Conn.,
a corporation of Connecticut

Application July 30, 1952, Serial No. 20,812

Term of patent 14 years

(Cl. D81—10)

To all whom it may concern:

Be it known that I, Edward D. Ringwall, a citizen of the United States, residing at West Haven, in the county of New Haven and State of Connecticut, have invented a new, original, and ornamental Design for a Combination Outdoor Fireplace and Grill, of which the following is a specification, reference being had to the accompanying drawing, forming part thereof.

Fig. 1 is a front elevation of a combination outdoor fireplace and grill showing my new design; and

Fig. 2 is a front perspective view thereof.

I claim:

The ornamental design for a combination outdoor fireplace and grill, substantially as shown.
EDWARD D. RINGWALL.
